GEORGE E. FREY, OF STEUBENVILLE, OHIO, ASSIGNOR OF ONE-HALF TO R. E. SNIDER,
OF MINGO JUNCTION, OHIO.

RAIL-CHAIR.

1,328,917.

Specification of Letters Patent. Patented Jan. 27, 1920.

Application filed August 2, 1919. Serial No. 314,843.

To all whom it may concern:

Be it known that I, GEORGE E. FREY, a citizen of the United States of America, and resident of Steubenville, county of Jefferson, and State of Ohio, have invented certain new and useful Improvements in Rail-Chairs, of which the following is a specification.

This invention relates broadly to rail chairs, and more particularly to a combined rail chair and clamp; and it has for its primary object to provide, in association with a metallic crosstie of approximately trough shape, a chair adapted for the reception thereon of a railway rail, and means whereby such rail may be securely clamped upon said chair.

A further object is to provide a device of the character mentioned embodying means whereby adjustment of the rail to compensate for wear on the inner side of the head thereof may be readily effected.

With these and other important objects in view, the invention resides in the features of construction, arrangement of parts and combinations of elements which will hereinafter be exemplified, reference being had to the accompanying drawings, in which—

Figure 1 is a top plan view of the invention with a rail mounted in place thereon;

Fig. 2 is a sectional elevation of the same, the section being taken on line 2—2, Fig. 1;

Fig. 3 is a transverse section on line 3—3, Fig. 1;

Fig. 4 is an enlarged perspective view of the rail chair;

Fig. 5 is a similar view of the rail clamp; and—

Fig. 6 is a similar view of the filler member.

Referring to said drawings, in which like designating characters distinguish like parts throughout the several views—

1 indicates a metallic crosstie which is of open trough shape, preferably approximately rectangular in cross section. Mounted upon said crosstie is a rail chair which comprises a flat horizontal seat 2 with opposite integral vertically disposed supporting members or legs 3 which lie closely against the inner surfaces of the upright side walls

of the crosstie being attached to said side walls by means of bolts or rivets 4, and which preferably have their lower edges resting upon the base of said crosstie. Also formed 55 integral with the seat 2 at each of the opposite sides thereof are two upright guard flanges 5 which are located in alinement and which have their adjacent ends spaced apart, as shown.

Located intermediate the alined guard flanges 5 at each of the opposite sides of, and preferably in the same plane with, the seat 2 is a laterally extending wing 6 having therein an aperture 7 of suitable shape and 65 dimensions. Said apertures are designed for the reception of the arms 9 of a rail clamp which consists of a horizontal bar 8 terminated at opposite ends by said arms 9. Said clamp, which is initially of approximately 70 U-shape, is designed to be elevated beneath the rail chair, with its arms 9 rising vertically through the apertures 7 in the wings 6, until the bar 8 rests firmly against the under side of the seat 2, whereupon said arms are 75 bent inward into overlying clamping relation to opposite sides of the base of a rail 10 resting upon said seat.

The opposite guard flanges 5 of the rail chair are spaced apart a suitable distance in 80 excess of the width of the base of the rail 10 which is to be mounted upon said chair, such distance being approximately one-half inch. The rail chairs are relatively mounted so that, when new track rails are being placed, 85 the proper track gage will be provided for by mounting the outer edges of the rail bases in closely abutting relation to the adjacent guard flanges. There will, therefore, remain an open space, approximately one-half 90 inch in width as aforesaid, between the inner edge of the base of the rail and the adjacent guard flanges. To provide for the filling of this open space, I seat upon the chair, prior to mounting the rail thereon, a filler member 95 11 which comprises a bar 11^a having a thickness approximately the width of said space, a length in excess of that of the rail chair, and a height approximating that of said guard flanges. Formed integral with said bar 11^a at each of its opposite ends is an angular foot piece 11^b adapted to closely un-

derlie the base of the rail 10. As is obvious, said bar 11^a serves to maintain the rail in fixed position with the outer edge of its base abutting the outer flanges of the chair.

- 5 When the inner faces of the heads of the rails 10 have become worn by the flanges of the wheels passing thereover to the extent that readjustment of the track gage becomes necessary, the rails may be removed from 10 the chair and the filler member shifted from the position above described to a similar position against the flanges at the outer edge of the chair, whereupon the rail may be remounted upon the chair between said filler 15 member and those flanges located at the inner edge of the chair, in which position said rail will be located nearer the opposite track rails by a distance equal to the thickness of the bar 11^a of the filler member.
- 20 A notch 12 of suitable depth is provided in the bar 11^a of the filler member 11 for the reception of the adjacent arm 9 of the rail clamp when said arm is bent over into clamping relation to the rail.
- 25 What is claimed is—
1. A rail chair and clamp comprising a flat seat for a rail base, said seat having means whereby it may be attached to a trough-shaped crosstie, an integral wing extending laterally from each lateral edge of said seat, each of said wings having an opening therein, and a bar disposed in underlying relation to said seat and having terminals turned upward and inward into clamping relation to the opposite sides of the base of a rail mounted on said seat, said terminals being received in the openings in said wings.
  2. A combined rail chair and rail clamp, comprising a flat seat for the reception of a rail base, integral down-turned supports at the ends of said seat for attachment to a crosstie, integral laterally extending wings at the sides of said seat, said wings having openings therein, and a bar disposed in underlying relation to said seat and having terminals bent into overlying clamping relation to opposite sides of the base of a rail mounted on said seat, said terminals being disposed in said wing openings.
  3. A combined rail chair and rail clamp, comprising a flat seat for the reception of a rail base, integral down-turned supports at the ends of said seat for attachment to a crosstie, integral laterally extending wings at the sides of said seat, said wings having openings therein, a bar disposed in underlying relation to said seat and having terminals bent into overlying clamping relation to opposite sides of the base of a rail mounted on said seat, said terminals being disposed in said wing openings.
  4. A rail chair and clamp comprising a horizontal seat having a pair of aligned up-turned flanges at each side thereof, the opposite flanges being spaced apart a distance in excess of the width of the base of the rail which rests upon said seat, a laterally extending wing integral with said seat at each side thereof, each of said wings being located intermediate the adjacent aligned

said seat, and a filler member adapted for mounting upon said seat on either side of the rail between the guards and the rail base whereby the rail is held in a position where in the opposite edge of its base is maintained 70 in abutting relation to the adjacent guards.

4. A combined rail chair and rail clamp, comprising a flat seat for the reception of a rail base, integral down-turned supports at the ends of said seat for attachment to a 75 crosstie, integral laterally extending wings at the sides of said seat, said wings having openings therein, a bar disposed in underlying relation to said seat and having terminals bent into overlying clamping relation 80 to opposite sides of the base of a rail mounted on said seat, said terminals being disposed in said wing openings, guards formed on opposite sides of said seat at each side of said wings, the opposite guards 85 being spaced apart a distance in excess of the width of the rail base which is to rest upon said seat, and a filler member adapted for mounting upon said seat on either side of the rail base to occupy the space between 90 one edge of the latter and the adjacent guards whereby the opposite edge of said base is maintained seated against the opposite guards, said filler member having portions underlying said base. 95

5. A combined rail chair and rail clamp, comprising a flat seat for the reception of a rail base, integral down-turned supports at the ends of said seat for attachment to a crosstie, integral laterally extending wings 100 at the sides of said seat, said wings having openings therein, a bar disposed in underlying relation to said seat and having terminals bent into overlying clamping relation to opposite sides of the base of a rail 105 mounted on said seat, said terminals being disposed in said wing openings, guards formed on opposite sides of said seat at each side of said wings, the opposite guards being spaced apart a distance in excess of the width of the rail base which is to rest 110 upon said seat, and a filler member adapted for mounting upon said seat on either side of the rail base to occupy the space between one edge of the latter and the adjacent guards 115 whereby the opposite edge of said base is maintained seated against the opposite guards, said filler member having angular end portions disposed outward of the ends of said seat in underlying relation to the 120 rail.

6. A rail chair and clamp comprising a horizontal seat having a pair of aligned up-turned flanges at each side thereof, the opposite flanges being spaced apart a distance in excess of the width of the base of the rail which rests upon said seat, a laterally extending wing integral with said seat at each side thereof, each of said wings being located intermediate the adjacent aligned 125

flanges and having an aperture therein, a bar disposed in closely underlying relation to said seat, said bar having terminals which are projected upward through said wing-
5 apertures and which are bent into overlying clamping relation to the base of said rail, and a filler member mounted upon said seat between one edge of the rail base and the ad-

jacent flanges, said member being reversible and applicable at either side of the rail. 10

In testimony whereof I affix my signature in presence of two subscribing witnesses.
